SEWING BASKET

Filed April 11, 1928

UNITED STATES PATENT OFFICE

WILLIAM U. MURRISH, OF OAKLAND, CALIFORNIA

SEWING BASKET

Application filed April 11, 1928. Serial No. 269,232.

The invention forming the subject matter of this application relates to sewing baskets.

The primary object of the invention is to provide a sewing basket which is compact and is formed in the shape of a spool, the upper part of the spool-like basket serving as a hood, so that when the hood is removed, it uncovers a plurality of compartments adapted to receive a variety of sewing implements.

Another object of the invention is to provide a base having an upright partition frame thereon which separates the space above said base into a number of compartments in accordance with the size and the variety of the sewing implements in every day use, and a cylindrical cover which may be removably placed upon the base so as to cover the compartments, the partition being so designed as to extend above the cylindrical cover, and it is adapted to be used as a handle for carrying the sewing basket.

Another object of the invention is to provide a sewing basket which is highly useful and simple in construction. Attractiveness of appearance, convenience of arrangement, lightness and comparative inexpensive of manufacture are further objects which have been borne in mind in the production and development of the invention.

In this specification and the annexed drawing, the invention is illustrated in the form which is considered to be the best, but it is to be understood that the invention is not limited to such form, because it may be embodied in other forms; and it is also to be understood that in and by the claims following the description, it is desired to cover the invention in whatsoever form it may be embodied.

The invention is clearly illustrated in the accompanying drawing, in which—

Figure 1 is a cross sectional view of the sewing basket;

Figure 2 is a sectional plan view of the sewing basket, the section being taken along the line 2—2 of Figure 1; and

Figure 3 is a side elevation of the sewing basket showing in dotted lines the position of the hood partly removed.

Referring to the accompanying drawings, wherein similar reference characters designate similar parts throughout, the various figures described above adequately illustrate my invention, and the following detailed description is commensurate with the above mentioned drawings in enabling an artisan to construct and assemble the constituent parts of the same.

In carrying out my invention, I employ a base, denoted in its entirety by the numeral 5. The base is recessed as at 6. In the recess are segmental platforms 7 and 9, separated from the rim of the base 5 by arcuate grooves 11, said grooves being concentric with the rim. A central platform 8 of substantially rectangular shape is disposed between the segmental platforms 7 and 9 and is separated therefrom by grooves 12. The tops of said platforms are at a level with the top of the rim of the base 5. In order to divide the space above the recess 6 into separate compartments, walls 13 are secured into the grooves 12 in any conventional manner, such as gluing the walls in the grooves 12.

Transverse partitions 14 extend between the walls 13 and are secured to the sides of the central platform 8. Transverse end partitions 15 are disposed at the opposite ends of said walls 13 and are supported thereat in a manner to be hereinafter described. The end partitions 15 are considerably shorter than the central partitions 14, as it is clearly shown in Figure 1.

In order to firmly secure the partitions 14 to the walls 13 a braid 16 is employed which is inserted thru slots 17 and 18 respectively in the partitions 14 and the walls 13. The ends of the braid 16 are then fastened together by sewing or in any other conventional manner. The shorter end partitions 15 are held in place at the ends of the walls 13 by means of rings 19 which pass thru corresponding holes adjacent to the ends of the partitions 15 and the walls 13. Spool rods 21 extend from the platforms 7 and 9. There are three spool rods on each segmental platform. On the outside face of the partitions 14 are needle pads 22 extending from the top of the walls 12 to a level slightly above

the level of the upper edge of the partitions 15.

5 A cylindrically shaped hood 23 is of such a diameter that it may be easily placed upon the base and into the grooves 11. A cover 24 of the hood 23 is shown as braided to the upper end of the hood 23, but it may be secured thereto in any other manner. It is possible to finish the upper edge integral with 10 the hood 23 and in the shape of a rim similar to that of the base so as to still further approximate the appearance of a spool. The partitions 14 extend above the cover 24 thru an aperture 25 is said cover and the extensions 26 of said partitions 14 are so shaped as to form a convenient handle for carrying the sewing basket. It is evident that the sewing basket may be readily carried by simply grasping the handle 26 which, by means of 15 the partitions 14, will raise the base, while the cylindrical hood 23 will remain on the base resting in the grooves 11. When the hood 23 is removed, then all the partitions are simultaneously uncovered.

25 As the central compartment above the platform 8 is always accessible thru the aperture 25, it is desirable to keep a pair of scissors or the like therein. Spools of thread 27 are slipped upon the spool rods 21 and are held 30 in place so that the thread ends may be readily found, and the spool 27 rotates on the rod 21 while the thread is unwound therefrom.

35 The needles are kept in the needle pad 22. All the other sewing implements may be as sorted in the compartments formed between the partitions 14 and 15. Of course, it is optional how the different compartments in the sewing basket are utilized, but it is readily seen that all the compartments are easily accessible when the hood is removed. It will be 40 recognized that a particularly compact sewing basket is provided to accomplish the efficient assortment of different sewing implements in separate compartments and to hold 45 the same securely covered when not in use. The hood is so decorated that when it is placed upon the base 5, the whole basket presents the appearance of a large spool.

50 The sewing basket combines light weight and compact arrangement with a strength of construction and attractiveness of appearance, especially adapting it for its use.

Having thus described my invention, what 55 I now claim as novel and desire to secure by Letters Patent is:

1. A sewing basket comprising a base, long partitions extending from said base forming a central compartment; short partitions extending from said base forming compartments beside said central compartment, a removable hood for covering said compartments; two of said central partitions extending through said hood so as to form handles thereabove.

65 2. A sewing basket comprising a base, long

partitions extending from said base forming a central compartment; short partitions extending from said base forming compartments beside said central compartment, a removable hood for covering said compartments; two of said central partitions extending through said hood so as to form handles thereabove, said hood having an aperture 70 therein above said central compartment.

3. A sewing basket comprising a base, long partitions extending from said base and forming a central compartment; short partitions extending from said base forming compartments beside said central compartment; a removable hood for covering said 75 compartments; two of said central partitions extending through an aperture in said hood disposed above said central compartment, said extension forming handles thereby; and a plurality of spool rods outside of said central compartment extending from said base. 80

4. A sewing basket comprising a recessed base; two partitions extending across said recess; central partitions extending from said base and secured to said cross partitions so as to form a central compartment; short partitions outside of said central partitions and disposed between said cross partitions; spool rods secured outside of said cross partitions, and a removable hood for covering all the said 90 compartments. 95

5. A sewing basket comprising a recessed base; two partitions extending across said recess; central partitions extending from said base and secured to said cross partitions so as to form a central compartment; short partitions outside of said central partitions and disposed between said cross partitions; spool rods secured outside of said cross partitions, and a removable hood for covering all the 100 said compartments; said hood having an aperture therein disposed above said central compartments, said central partitions extending through said aperture and adapted to 105 form a handle thereabove. 110

6. A sewing basket comprising a recessed base; a central platform and two side platforms in said recess; cross partitions extending alongside said side platforms, central partitions secured to the opposite sides of said central platform and extending across between said cross partitions thereby forming a smaller compartment thereat; spool rods extending from said side platforms, and a removable hood for covering said compartments and spool rods. 115

7. A sewing basket comprising a recessed base; a central platform and two side platforms in said recess and said platforms being separated from each other and a rim of the base by grooves; cross partitions extending alongside said side platforms and being secured in grooves thereat; central partitions secured to the opposite sides of said central platform and extending across between said 125 130

cross partitions so as to form a central compartment above said central platform; short partitions secured to the opposite ends of said cross partitions thereby forming smaller compartments thereat; spool rods extending from said side platforms, and a removable hood for covering said compartments and spool rods.

8. A sewing basket comprising a recessed base; a central platform and two side platforms in said recess and said platforms being separated from each other and a rim of the base by grooves; cross partitions extending alongside said side platforms and being secured in grooves thereat; central partitions secured to the opposite sides of said central platform and extending across between said cross partitions so as to form a central compartment above said central platform; short partitions secured to the opposite ends of said cross partitions thereby forming smaller compartments thereat; spool rods extending from said side platforms, a removable hood for covering said compartments and spool rods, and handles formed by the upper ends of said central partitions extending through said hood.

9. A sewing basket comprising a recessed base; a central platform and two side platforms in said recess and said platforms being separated from each other and a rim of the base by grooves; cross partitions extending alongside said side platforms and being secured in grooves thereat; central partitions secured to the opposite sides of said central platform and extending across between said cross partitions so as to form a central compartment above said central platform; short partitions secured to the opposite ends of said cross partitions thereby forming smaller compartments thereat; spool rods extending from said side platforms, and a removable hood for covering said compartments and spool rods, and handles formed by the upper ends of said central partitions extending through said hood, said base and said hood being so formed as to simulate a spool when assembled.

In testimony whereof I affix my signature.
50 WILLIAM U. MURRISH.
